No 17804

D17804

UNITED STATES PATENT OFFICE.

HENRY SCHUERMAN, JR., OF CARROLLTON, KENTUCKY.

DESIGN FOR A BEDSTEAD.

SPECIFICATION forming part of Design No. 17,804, dated October 18, 1887.

Application filed July 2, 1887. Serial No. 243,296. Term of patent 3½ years.

To all whom it may concern:

Be it known that I, HENRY SCHUERMAN, Jr., of Carrollton, in the county of Carroll and State of Kentucky, have invented certain new and useful Improvements in Designs for Furniture; and I do hereby declare the following to be a full, clear, and exact description of the invention, such as will enable others skilled in the art to which it pertains to make and use it, reference being had to the accompanying drawing, which forms part of this specification.

My invention relates to designs for bedsteads; and it consists in the ornamental shape and configuration, which will be more fully described hereinafter, whereby a new, useful, and pleasing effect is produced.

The accompanying photographic illustration represents a design for a bedstead embodying my invention.

20 A represents a face, and extending away from this face on opposite sides are the curved lines B, which have ornamental edges, as shown. Rising from the top of the head, just above the eyes, is the representation of a leaf, C, having irregular edges. Upon each side of the face, which is placed at the center of the top edge of the bedstead, are the two spirals D, which curve outward and downward toward opposite edges, and which terminate in scrolls E, which 25 extend at an angle thereto, and under the scrolls are the ornamental designs F. Extending outward in opposite directions from the spirals D are the ornamental designs G, which represent, to some extent, oak-leaves. The face A and the parts B, C, and G form a raised center-piece, which is placed upon the top of the bedstead and makes a very ornamental top piece therefor.

The molding H, having a corrugated edge, 30 I, extends across the top of the bedstead just above the shoulder or flange J. Under the flange J is the curved surface L, and at each end of this curved surface is a square, M, having shouldered edges, as shown. Under the 35 curved surface L is a panel, upon which are represented a number of balls or circles, N, which are surrounded by rings O. At each end of this panel, upon which the balls and circles are represented on raised backgrounds, are 40 formed a cluster of leaves and berries, P. Under these leaves and berries P are formed the

shoulders Q, which project a suitable distance outward, as shown, and just under the shoulders Q are formed the ornamental designs R.

The shoulder and the ornamental design R 55 form the head of a column or post at each end of the bedstead for supporting all that part of the top piece which extends above them. The pillars or posts S are ornamented down their center by scale-like figures, which extend in a 60 vertical line from one shoulder T at the top to a corresponding shoulder T at the bottom. The lower ends of these columns or posts are formed by oblique squares U, upon which are 65 formed sunken panels, and on these panels are formed the ornaments V, as shown.

Between the pillars or posts S are formed a large sunken panel, W, and in this panel is formed a second sunken panel, X, having side and end edges curved as shown. Below the 70 panel W is formed a curved surface, Y, which is grooved at regular intervals from one end to the other.

The foot-board has the shoulder or flange Y formed upon its top, from which the edges are 75 curved upward, and at a suitable distance below this flange are formed the small oblong curved figures A', which are placed in a row and extend from one side of the article to the other. Below these figures A' is formed the 80 shoulder B', which is supported at each end by the oblong panel C'. Under the shoulder is formed the curved surface D', which extends across from one panel C' to the other. Under the curved surface D' is formed a second row 85 of balls, N, which are surrounded by the rings O. Under this row of balls and rings is formed a projecting shoulder or flange, E', which extends any suitable distance outward over the top of a second panel, W, and in which is a 90 second sunken panel, X, having curved side and end edges. At each end of this panel W is a pillar or post, S, having an ornamental figure, R, and molding or shoulder T at its top. The lower portions of this pillar S are formed 95 by oblong panels U, which have vertical grooves extending down their surface. Below this panel U are formed outwardly-curved feet F', upon which are formed suitable ornamental designs, G'. Below the panel W is formed a 100 molding, H', and under this molding H' is formed a row of scalloped figures, I', which ex-

tend entirely across the panel U. Under the scalloped figures I' is a suitable molding, J'.

Having thus described my invention, I claim—

5 1. In a bedstead herein shown and described, a top panel provided with the face A, curved lines B, extending therefrom, the leaf C, rising from the head, the scrolls D, and the curved lines G, extending outward from the scrolls, 10 as shown.

2. In a bedstead herein shown and described, the upper central section consisting of the curved surface L, the balls N, surrounding

rings O, the sunken panels W X, and the pillars or posts, as described. 15

3. A design for a bedstead herein shown and described, consisting of the top panel having the flanges B', the curved surface L, balls N, surrounding rings O, squares M, flanges E', sunken panels W, and pillars S, as set forth. 20

In testimony whereof I affix my signature in presence of two witnesses.

HENRY SCHUERMAN, JR.
